UNITED STATES PATENT OFFICE.

NEWTON A. WOLCOTT, OF WARREN, OHIO, ASSIGNOR TO THE PACKARD ELECTRIC COMPANY, OF WARREN, OHIO, A CORPORATION OF OHIO.

MEANS OF TESTING INSULATED WIRES.

No. 856,012.

Specification of Letters Patent.

Patented June 4, 1907.

Application filed May 5, 1906. Serial No. 315,359.

To all whom it may concern:

Be it known that I, NEWTON A. WOLCOTT, of Warren, in the county of Trumbull and State of Ohio, have invented certain new and useful Improvements in Means for Testing Insulated Wires; and I do hereby declare the following to be a full, clear, and exact description of the invention, such as will enable others skilled in the art to which it appertains to make and use the same.

The object of this invention is to provide means for detecting imperfections in the insulation of wires or cables without actually energizing the core save where there is imperfect insulation.

A further object is to provide means of the character stated for testing cables as they are being manufactured, that is to say, a device which will be continuously in operation as the cables come from the machines, or at any other stage of forming the insulation.

The invention will be hereinafter fully set forth and particularly pointed out in the claims.

In the accompanying drawings, Figure 1 is an elevation of the means for carrying out my invention where continuous service is required. Figs. 2, 3 and 4 show modified forms.

Referring to the drawings, 1 designates a base upon which are mounted two metallic dielectric contacts 2 and 3, preferably in the form of spring sleeves or cylinders having central openings for the passage of the insulated wire or cable 4, with which the contacts have a constant brushing engagement. These contacts are mounted in supports 5 and are in axial line with each other and with a guide 6.

7 designates a transformer, the terminals of the secondary wiring 8 of which are secured to posts 9 on the supports 5, thus electrically connecting the secondary with the contacts 2 and 3.

The primary 10 is connected through a switch 12 to a generator 13, or other source of electrical supply. Within the primary circuit I locate an automatic cut out 14 for effecting the actuation of a bell or other alarm 15, which cut out will be automatically operated instantly the secondary circuit is closed, since the closing thereof varies the current in the primary circuit, and this variation results in the operation of the automatic cut out. This may or may not cut out the

transformer. The cut out is conventionally shown as embodying a solenoid coil 16 and an armature 17 in the form of a bell crank lever which normally holds a switch 18 and closes the circuit through the solenoid. The attraction of the armature by the solenoid will effect the automatic disengagement or release of the switch 18 and the closing of the bell circuit, and, according to the form shown in Fig. 1, the opening of the primary circuit, the contact with the solenoid wiring being broken.

The arrangement described is especially applicable where continuous service is required, as in testing cables as they come from the machine. Any marked weakening of the dielectric strength will reduce the resistance in the secondary circuit, and this in turn will effect the automatic release of switch 18, thereby giving an alarm when a poorly insulated spot is passing either of the contacts. In other words, the secondary voltage of the transformer is somewhat less than the puncture voltage of the two dielectrics in series, and hence the alarm is given when there is a failure on one side, or even a marked variation in the dielectric strength. This will indicate a weakness in the cable although perhaps not sufficient to break down the dielectrics.

It is manifest that the idea dominating the present invention may be carried out in various ways, and with other means than that described. In Fig. 2 I have shown the primary wiring in constant closed relation to the solenoid cut out, so that the release of the switch will merely cause the actuation of the alarm.

Where the tester is not employed continuously, or where a particular form of test is desired, I may substitute an induction coil for the transformer, (see Fig. 3) in which event the secondary winding has connected thereto adjustable sparkers 21, and within the primary winding, which has a switch connection to a battery 22, is a make and break contact device 23. The voltage required to continuously jump the spark gap is more than sufficient to break down the insulation between the exterior of the cable and the core thereof, but not sufficient to break down two such points of insulation in series. Hence the tester, thus adjusted, will not break down the cable insulation, with the two di-

electrics in series, but as soon as a defective point of insulation engages one of the brushing contacts, say 3, the puncture voltage of the two dielectrics in series is sufficiently lessened to permit a ready transfer of energy from the contact 3 to the core center. This will leave but a single dielectric between the other contact, 2, and the common core, the potential being more than sufficient to break through this insulation. Thus is established a complete secondary circuit, and vigorous sparking will occur at the contacts instead of at the sparkers. According to the means last described the attendant becomes aware of the defect in the insulation by the cessation of the sparks at the spark gap, and the vigorous sparking at the cable contacts. The sound of the sparking at such contacts is quite different from that at the sparkers, and this in itself affords means for indicating or detecting the defect if the operator does not happen to be looking the instant the sparking occurs at the contacts.

In Fig. 4 I have shown a source of potential 24 applied direct to the contacts without the interposition of any transforming device, and circuit breaker 25 may or may not be included in the circuit. If included, it may be used as indicated in either Figs. 1 or 2.

I claim as my invention:

1. In an insulated cable tester, two dielectric contacts with which the cable engages, and means for supplying to such contacts a current of a potential less than the voltage of the two dielectrics in series but sufficient to energize one contact when the other contact energizes the core of the cable.

2. In an insulated cable tester, two dielectric contacts with which the cable engages, a source of electrical supply, and primary and secondary windings, the former being connected to a source of supply, and the latter to the contacts for supplying thereto a voltage less than the puncture voltage of the two dielectrics in series.

3. In an insulated cable tester, two dielectric contacts with which the cable engages, a source of electrical supply, primary and secondary windings, the latter being connected to said contacts and the former to the source of supply, and an alarm connected to the primary winding, such alarm being actuated when there is a marked variation or failure in the dielectric strength of the secondary.

4. In an insulated cable tester, two dielectric contacts with which the cable engages, a source of electrical supply, primary and secondary windings, the latter being connected to said contacts and the former to the source of supply, and means for cutting out the pri-

mary when there is a marked variation or failure in the dielectric strength of the secondary.

5. In an insulated cable tester, two dielectric contacts with which the cable engages, a source of electrical supply, primary and secondary windings, the latter being connected to said contacts and the former to the source of supply, an alarm connected to the primary winding, and means for causing such alarm to be actuated and cut out the primary when there is a marked variation or failure in the dielectric strength of the secondary.

6. In an insulated cable tester, two dielectric contacts with which the cable engages, a source of electrical supply, and a transformer or induction coil, the secondary winding of which is connected to said contacts, the potential being less than the voltage of the two contacts in series, but sufficient to close the secondary circuit when either contact energizes the core of the cable through a point of insufficient insulation.

7. An insulated cable tester having two dielectric contacts, and means for supplying an electric current to said contacts of such potentiality that the contacts in series are quiescent, either being thrown in circuit with the other through the core of a cable when an insufficiently insulated portion thereof engages such other contact.

8. The herein-described tester for insulated cables, comprising two contacts with which the cables have a wiping contact, a transformer, having its secondary winding connected to said contacts, and a source of electrical supply connected to the primary winding of such transformer, the secondary circuit being closed through the cable core and either of the contacts when the other contact is engaged by a defective section of insulation.

9. The herein-described tester for insulated cables, comprising a base, two contacts having openings for a cable, terminal posts mounted on said contacts, a transformer, having its secondary winding connected to said terminal posts, a source of electrical supply to which the primary winding is connected, a bell, a switch therefor, a solenoid coil, and an armature for normally holding such switch open.

In testimony whereof, I have signed this specification in the presence of two subscribing witnesses.

NEWTON A. WOLCOTT.
